UNITED STATES PATENT OFFICE

GRA C. BROWN AND GREGORY F. McNULTY, OF MASSILLON, OHIO, ASSIGNEES TO THE
REYNOLDS MACHINE COMPANY, OF MASSILLON, OHIO, A CORPORATION OF OHIO

SCREW-DRIVING MACHINE

Application filed December 14, 1928. Serial No. 325,983.

The invention relates to machines for driving screws and is particularly adapted for use in shops and factories for driving machine screws to fasten two or more parts together 5 with greater speed and accuracy than is possible manually.

The object of the improvement is to provide a machine of this character having a magazine for containing the screws to be used in the 10 machine, an improved escapement device for receiving the screws from the magazine one at a time and delivering them to a vertically movable foot which carries each screw to the work, a screw driver being co-ordinated with 15 the movement of the foot for driving each screw into the work, means for automatically disengaging the foot from the screw and raising the foot above the driver to permit the screw to be driven home; means for driving 20 screws into soft metals such as aluminum without the necessity of tapping holes in the metal to receive the screws; and to provide an indexing apparatus for carrying small pieces of work, the same being co-ordinated with 25 the movement of the screw driver and foot to position the work beneath the same as the foot and screw driver are lowered.

An embodiment of the invention is illustrated in the accompanying drawings, in 30 which

Figure 1 is a front elevation of the improved screw driving machine to which the invention pertains;

Fig. 2, a side elevation showing the left side 35 of the complete machine;

Fig. 3, a similar view of the right side of the machine;

Fig. 4, an enlarged plan view of the machine;

Fig. 5, a plan section of the magazine and 40 escapement mechanism;

Fig. 6, a front elevation of the magazine and escapement;

Fig. 7, a vertical transverse section through 45 the magazine, taken substantially on the line 7-7, Fig. 5;

Fig. 8, an enlarged fragmentary section through the escapement mechanism, taken 50 substantially on the line 8-8, Fig. 5;

Fig. 9, a detached perspective view of the escapement mechanism;

Fig. 10, a vertical sectional view taken substantially on the line 10-10, Fig. 4, showing the driving head and associated parts; 55

Fig. 11, an enlarged sectional view through the driving head taken substantially on the line 11-11, Fig. 10;

Fig. 12, a section taken substantially on the line 12-12, Fig. 4, showing the cams and cam 60 levers;

Fig. 13, a detail sectional view showing the clutch release shaft and associated parts;

Fig. 14, a detail perspective view of a portion of the clutch release shaft and the throw-out cam; 65

Fig. 15, a perspective view of the gearing and cams for operating the apparatus;

Fig. 16, a detail sectional view with parts broken away, showing the cross slide and the 70 vertical slide which carries the foot, the screw driver and foot being shown in raised position;

Fig. 17, a similar view showing the foot lowered and the driver in the act of driving 75 a screw into the work;

Fig. 18, a similar view showing the driver at the end of the driving stroke and the foot raised;

Fig. 19, a plan section taken substantially 80 on the line 19-19, Fig. 16; and

Fig. 20, a section of the friction mechanism in the driving head taken substantially on the line 20-20, Fig. 11.

Similar numerals refer to similar parts 85 throughout the drawings.

Referring more particularly to the embodiment illustrated in the accompanying drawings, the machine may be supported upon an upright or standard 21, having the base 22 at 90 its lower end and the housing 23 at its upper end, the mechanism being housed in and upon the same.

The work carrying table 24 is provided with the slide portion 25 slidable upon the 95 vertical guides 26, on the standard, and adapted to be vertically adjusted thereon by the nut 28 which is threaded upon the stationary screw 29 and arranged to be rotated through the spiral gear 30 and hand crank 31. 100

The mechanism may be driven by a motor 32 which may be mounted upon the base 22, the shaft 33 thereof having a pulley 34 fixed thereon for connection of a belt 35 which extends over a pulley 36 fixed upon the main driving shaft 37 journaled in a bearing 38 upon the housing.

A spiral gear 39 is fixed upon the opposite end portion of the shaft 37 within the gear housing 40 and meshes with the spiral pinion 41 upon the screw driving shaft 42 located within the driving head housing 43 which is mounted upon the arm or bracket portion 44 of the main housing.

A spiral pinion 45 is fixed upon an intermediate portion of the shaft 37 and meshes with a similar pinion 46 upon the worm shaft 47, the worm 48 thereon meshing with the worm gear 49 upon the clutch and cam shaft 50.

A spiral gear 51, fixed upon a shaft 52, also meshes with the spiral pinion 45. A spiral pinion 53 is fixed upon the shaft 52 and meshes with a similar pinion 54 upon the worm shaft 55, the worm 56 thereon meshing with the worm gear 57 upon the shaft 58.

A spiral pinion 59 is fixed upon the shaft 58 and meshes with a similar pinion 60 upon the brush shaft 61 upon which is mounted the brush 62 located within the magazine shown generally at 63.

A pinion 64 is fixed upon an intermediate portion of the shaft 58 and meshes with a gear 65 upon the vertical shaft 66 which is journaled in a central bearing lug 67 carried by the radial arms 68 of the magazine. The conical dial 69, which rotates within the lower portion of the magazine, is fixed upon the lower end of the shaft 66.

The magazine 63 is substantially circular in plan view and comprises the annular side wall 70 having an inturned beveled flange 71 formed or fixed to its lower edge. The conical dial 69 is inclined downward toward its periphery, which is located in the same horizontal plane with the beveled flange 71 and spaced therefrom a distance corresponding to the diameter of the shanks of the screws to be deposited thereon, and the circumferential edge of the dial is likewise beveled at its upper face as at 72, corresponding with the bevel of the flange 71.

The periphery of the dial is spaced sufficiently from the flange 71 to form a circular space or runway into which the stems of the screws, supplied to the magazine, fall and are suspended by reason of the heads thereof resting on the beveled edges of the dial and flange 71.

The circular brush 62 is of such diameter that it will brush back any surplus screws which may be carried forward by the dial and allow only those to pass which are suspended by their heads in the annular runway.

A guard ring 73 is connected to the inner

surface of the magazine and extends from a point beneath the center of the brush to a point beyond the escapement mechanism which will be later described. This guard ring is spaced above the flange 71, and the beveled periphery of the rotating dial, a sufficient distance to allow the heads of the screws to pass freely beneath the ring when the screws are hanging vertically in the annular runway as indicated at A in Fig. 7. The ring, however, is sufficiently close to the annular runway to prevent any screws passing beneath the ring, excepting those which are suspended therein, in the proper position.

Connected to the inner face of the magazine and extending from the escapement mechanism to a point spaced from the rotary brush is a ring 75 which extends over the periphery of the dial and is spaced above the same and the flange 71 a proper distance to prevent screws from passing beneath said ring.

The improved escapement mechanism which permits of the delivery of the pendent screws one at a time to the foot 76, includes a segment 77 carried upon a bifurcated bracket arm 78 which is fixed upon the vertical shaft 79 as by the key 80 and nut 81, said shaft being journaled in a bearing boss 82 formed upon the outside of the magazine.

The segment 77 is located directly beneath the magazine and extends across the path of the screws suspended in the annular runway and acts as a stop for the screws indicated at A in Fig. 5.

A rocker arm 83 is fixed upon the upper end of the shaft 79 and connected as by a ball and socket joint, indicated at 84, to an arm 85 which is connected by a similar joint indicated at 86 to one arm 87 of a bell crank journaled upon the shaft 88.

The other arm 89 of said bell crank is connected, as by a ball and socket joint indicated generally at 90, to a link 91 adapted to be operated by a cam mechanism to be hereinafter described.

A slide plate 92 is fixed upon the top of the segment 77 as by the screws 93 and is provided in its free end with a notch 94 registering with similar notches 95 and 96 in the segment 77 and arm 78, respectively.

The notch 95 in the segment is in the form of an elongated slot within which is slidably located the feed slide 97 having at its rear or inner end an upright stud 98 projecting through a slot 99 in the slide plate and engaged by the bifurcation 100 in the sliding block 101.

This block is carried by a link 102, connected as by a screw 103, with the rocker arm 104 fixed upon the rocker shaft 88. A rocker arm 105 is fixed to the upper end of the shaft and connected as by a ball and socket joint 130

indicated at 106, to a link 107 leading to the cam mechanism above referred to.

The cam mechanism includes a hub 108 fixed upon the cam shaft 50 as by a key or spline 109. This hub is provided with a plurality of annular grooves 110, 111, 112 and 113 in which are located the cams 114, 115, 116 and 117, respectively.

A shaft 118 is located parallel to the cam shaft and mounted in bearings 119 upon the frame 120 connected to one side of the main housing as by the screws or bolts 121. Levers are mounted upon the shaft 118 for cooperation with the several cams.

The lever 122 is connected at one end to the link 91 and provided with the rollers 123 and 124 for cooperation with the cam 114. A similar lever 125 is journaled upon the shaft 118 and connected to the link 107. This lever is provided with a roller corresponding in position to the roller 123 for cooperation with the cam 115.

Each of the levers 122 and 125 has a rod 126 connected to its other end, said rod extending downward and rearward and slidably located through a lug 127 upon the frame 120, a coil spring 128 being located around the rods 126 and interposed between the lugs 127 and the collars 129 at the free ends of the rods, tending to normally urge the levers 122 and 125 toward the cam hub.

A lever 130 is journaled upon the shaft 118 and provided with a roller 131 adapted to cooperate with the cam 116. This lever is substantially L-shaped, the depending arm 132 thereof extending below the main housing and being connected to a link 133 which operates an indexing device which may be placed upon the table 24 for carrying small work and automatically positioning the same beneath the screw driver as will be later described.

This indexing device may comprise a base plate 134 adapted to be detachably mounted upon the work table 24 and having a shaft 135 journaled therein, upon which is mounted the indexing disk 136 provided with any suitable arrangement of dowel apertures 137 for carrying small pieces of work.

A ratchet wheel 138 is fixed upon the shaft 135 and adapted to be engaged by a pawl 139 carried upon a lever 140 which is journaled upon the shaft 135 and connected at its opposite end to the link 133. The pawl is pivoted intermediate its ends upon the lever 140 as indicated at 141 and is normally held in engagement with the ratchet wheel by means of a pull spring 142 connected to the tail end of the pawl and to the lever 140.

The cam 117 is adapted to engage the roller 143 carried upon the lever 144 which is also journaled upon the rocker shaft 118, said lever having an offset arm 145 adapted to cooperate with the arm 146 of a bell crank 147 pivoted as at 148 upon the main housing,

the other arm 148 thereof cooperating with the cross slide 149 mounted in the horizontal guide 150.

This cross slide has a vertical guide 151 in which is mounted the vertical slide 152 carrying the foot 76 which conveys the screws one at a time from the escapement mechanism to the work.

The guide 150 has a rod 154 fixed to one end thereof as by the end plate 155 and a coil spring 156 is located around said rod and interposed between the end plate and the opposite end wall 157 of the cross slide, tending to normally urge said cross slide toward the left as indicated in Figs. 16 and 18.

For the purpose of normally urging the vertical slide 152 upward, to the position shown in Fig. 16, a rod 158 is carried by the lug 159 of the vertical guide portion 160, of the cross slide. This rod extends upward and is slidable through the end plate 161 of the vertical slide, a coil spring 162 being located around the rod and interposed between the lug 159 and the plate 161.

The screw driving shaft 42 is journaled in a bearing 163, pivoted, as at 164, to the bifurcated end 165 of the lever 166 which is fulcrumed as at 167 to the upper end of a link 168, pivoted as at 169 upon the arm 44 of the main housing.

The other end of the lever 166 is provided with a counterweight 170 to normally urge the same toward the position shown in Fig. 10 and a rod 171 has slidably thereon a sleeve 172 pivoted to this end portion of the lever, the lower end of said rod being pivoted, as at 173, to the end portion of a lever 174, fulcrumed at its other end as at 175 upon the arm 44 of the housing. A coil spring 171^a is interposed between the sleeve 172 and a collar or nut 171^b upon the rod.

A roller 176 is carried intermediate the ends of the lever 174 and contacts with the periphery of the cam 177 fixed upon the cam shaft 50.

The screw driver shaft 42 is slidably keyed as at 178 within the tubular shaft 179, upon which is fixed the spiral pinion 41. Below the pinion 41 this tubular shaft is enlarged as at 180, the pinion resting against the upper shoulder 181 of said enlarged portion of the shaft.

An antifriction bearing 182 engages the lower shoulder 183 of said enlarged portion of the tubular shaft and is located within the annular recess 184 of the driving head housing 43. A similar antifriction bearing 185 forms a journal for the upper end portion of the tubular shaft 179 within the recess 186 in the upper portion of the housing 43. Nuts 187 and 188 are provided for maintaining the tubular shaft in adjusted position within said bearings.

The lower end of the shaft 42 is reduced as at 189 and located within the reduced upper

end of the driving sleeve 190, being fixed thereto as by the transverse pin 191, this driving sleeve being slidably mounted within the tubular shaft 179.

The lower end portion of the driving sleeve 190 is internally threaded as at 192 and the tube 193, which is located within the lower portion of the driving sleeve, is provided at its lower ends with threads engaging said internal threads of the driving sleeve and has the annular flange 194 engaging the lower end of the driving sleeve.

A bushing ring 195 is threaded within the lower internally threaded portion 196 of the tube 193 and provided at its lower end with the annular flange 197 engaging the lower end of the tube.

A ball bearing 198 is mounted against the internally shouldered portion 199 of the driving sleeve and journaled therein is a shaft 200 having the shoulder 201 around which is located the collar 202 pinned to said shaft as by the pin 203 directly beneath the ball bearing.

A ring 204 is threaded into the internally threaded upper portion 205 of the tube 193 and a coil spring 206 is interposed between said ring and a ring 207 which contacts with the internal annular flange 208 formed intermediate the ends of the tube 193.

The lower reduced end 209 of the ring 207 contacts with a series of friction disks 210 and 211 connected, respectively, to the tube 193 and the squared portion 212 of the shaft 200. The disks 210 are connected to the tube 193 by means of the lugs 213 received in the grooves 214 of the tube and the disks 211 are provided with squared central apertures 215 fitting upon the squared portion 212 of the shaft.

A socket sleeve 216 is connected to the lower end portion of the shaft 200 as by the transverse pin 217 and the lower end of said shaft is provided with a half-round lug 218 adapted to engage a similar lug 219 at the upper end of the screw driver tool 220, which is received within said socket sleeve and held fixed therein as by the set screw 221.

A lug 222 may be fixed upon the bearing 163 and fixed therein, as by the screw threads 223, is a depending push rod 224 held in adjusted position upon the lug as by the lock nut 225. This push rod is slidably located through a bore 226 in the arm 44 and arranged to contact with the lug 227 upon the vertical slide 152 to lower said slide and with it the foot 76 as shown in Fig. 17.

It should be noted that this foot is offset from the vertical slide as indicated at 228 and is provided with the slot 229 adapted to register with the notch 94 in the slide plate to receive a screw therefrom, in the position illustrated in Figs. 5 and 19.

The worm gear 49 is rotatably mounted upon the cam shaft 50 and adapted to be con-

nected thereto as by a clutch indicated generally at 231, said clutch having an annular groove 232 in which are located shoes 233 carried by the rods 234 slidably located through bearings 235 and connected to a crosshead 236 having a bifurcated portion 237 thereon.

A lever 238 is pivoted at its upper end to the bifurcation 237 and fulcrumed intermediate its ends, as at 239, upon a link 240 pivoted as at 241 upon the main housing. The lower portion of the lever is pivotally connected as at 242 to the clutch operating rod 243 which is slidably located through the main housing and may be parallel to the cam shaft.

This clutch rod has a collar 244 fixed thereon arranged to be engaged by one arm 245 of a bell crank pivoted as at 246 upon a bracket 247 carried by the housing, the other arm 248 thereof being pivotally connected as at 249 to the depending link 250.

This link extends downward along the side of the upright or standard 21 to a point adjacent to the base 22 where it is pivotally connected as at 251 to a bell crank segment 252 fulcrumed as at 253 upon the side of the standard or upright.

A link 254 is pivotally connected, as at 251^a, to the bell crank segment and extends forward in a substantially horizontal position, being pivotally connected at its other end, as at 255, to the upright arm 256 of a bell crank, the other arm 257 thereof being rigidly connected to the treadle 258 which is hinged or journaled as at 259 upon the base 22.

The rod 243 is slidably located through a bushing 260 in a bearing lug 261 formed upon the main housing and is slidably and rotatably located through a cam sleeve 262 having the V-shaped notches 262^a in its outer end adapted to be engaged by the similarly shaped cam lugs 263 upon the collar 264 which is fixed upon the outer end of the rod as by the set screw 265 and nut 266.

A radial lug 267 is formed upon the cam sleeve and adapted to be engaged by the peripheral lug 268 fixed upon the disk 269 as by the bolt 270. This disk is fixed upon one end of the cam shaft 50.

The operation of the machine is as follows: Assuming the parts to be in the normal or initial position, the screw driver and push rod 224 are raised as shown in Fig. 10, the screw driver shaft is continuously rotating, the conical dial 69 in the magazine is rotating in the direction of the arrow shown on Fig. 5, the brush 62 is rotating in the direction of the arrow shown on Fig. 7, the worm gear 49 is continuously rotating upon the cam shaft 50, the cam shaft itself remaining stationary.

The segment 77 is standing in the position shown in Fig. 5, preventing movement of the screws within the annular runway of the magazine, the feed slide 97 associated with

the segment is in the rearward or inoperative position shown in Figs. 8 and 9, the cross slide 149 is in the normal position and the vertical slide is in the raised position with the lug 227 positioned directly beneath the push rod 224 as shown in Fig. 16, the foot 76 being raised as shown in said figure and positioned to register with the notch in the segment 77 as shown in Fig. 5.

10 The operator then depresses the treadle 258 with his foot and through the link 254, bell crank segment 252, link 250 and bell crank 245-248 (see Fig. 13) and collar 244, the clutch operating rod 243 is pulled into the 15 position shown in Fig. 13, meshing the cam lug 263, upon the collar 264, with the cam recess 262^a in the sleeve 262.

Through the lever 238 the pins 234 are moved inward and through the shoes 233 the 20 clutch 231 is thrown in, coupling the worm gear 49 upon the cam shaft 50 and causing the same to rotate slowly.

The cam 114 will first engage the roller 124 upon the lever 122, and through the rod 25 91, bell crank 87-89, link 85, and rocker arm 83, the rocker shaft 79, and with it the segment 77, will be rotated toward the left until the notch 95 therein registers with the annular runway in the magazine, permitting 30 the foremost screw, shown at A in Fig. 5, to enter said slot.

The cam 114 will then contact with the roller 123 upon the lever 122, rocking the lever in the opposite direction and through 35 the bell cranks and links above described, the rocker shaft 79 will be moved back in the opposite direction, swinging the segment 77 back into the position shown in Fig. 5, preventing further movement of the screws in 40 the annular runway of the magazine and registering the notch 95 in the segment with the notch 229 in the foot 76.

The cam 115 will at that instant engage the roller upon the lever 125, pulling the link 45 107 and through the rocker arm 105, the rocker shaft 88 will be rocked, rocking the arm 104 thereof toward the segment 77. Through the link 102, block 101 and pin 98, the feed slide 97 will be moved outward, 50 ejecting the screw, shown at A in Fig. 8, from the notch in the segment and transferring the same into the notch 229 of the foot 76.

As soon as these operations have taken 55 place, the springs 128 will return the levers 122 and 125 to the normal or initial positions.

The cam 177 will then operate, through the lever 174, link 171 and spring 171^a and lever 166 to lower the screw driver and the push 60 rod 224 simultaneously. This lowering of the push rod will, through the lug 227, lower the vertical slide 152, and with it the foot 76, to the position shown in Fig. 17, positioning the screw A with reference to the work, 5 the screw driver, which is continuously rotat-

ing, engaging the screw and driving it into the work.

Before the screw is driven home, the foot 76 will be disengaged therefrom by the pressure of the arm 148 of the bell crank 70 146-148 against the cross slide, moving the cross slide, and with it the vertical slide, sufficiently to disengage the lug 227 of the vertical slide from beneath the push rod.

The spring 158 will immediately return 75 the vertical slide to the upper position as shown in Fig. 18, the lug 227 thereof resting against the side of the push rod 224. As the screw is driven home in the work, the cam 177 will operate, in conjunction with the counterweight 170, to return the screw driver and push rod to the initial or raised position shown in Figs. 10 and 16, permitting the spring 156 to force the cross slide, and with it the vertical slide, back to the initial position, 80 with the lug 227 positioned beneath the push rod, as shown in Fig. 16.

At this point the lug 268 upon the disk 269 will engage the radial lug 267 upon the cam sleeve 261, rotating the same to force the cam lug 263, upon the collar 264, out of engagement with the cam recess 262 of the sleeve, drawing the clutch operating rod 243 to the left and releasing the clutch, causing the cam shaft to stop rotating with the parts all returned to the initial position.

The work may be carried directly upon the table 24 or if it is desired to operate upon small pieces of work, the indexing attachment 90 may be mounted upon the table and the work positioned, by means of jigs or the like upon the indexing disk 136.

With each complete operation of the machine as above described, the cam 116 will 95 operate the L-shaped lever 130 and through the link 133, lever 140, pawl 141 and ratchet 138, the indexing disk will be moved a sufficient distance to bring a piece of work directly beneath the descending foot and screw driver in position to receive the screw carried 100 down thereby.

It should also be understood that the operation of the machine may be made continuous in order to continuously drive successive screws into work which may be conveyed to 115 the proper position beneath the screw driver by the indexing disk 136 or other suitable conveyor means.

This may be accomplished by removing the 120 peripheral lug 268 from the cam disk 269. Thus it will be seen that when the treadle is depressed, the operation of the machine will be started and will continue indefinitely since there is no means for throwing out the clutch at the end of each cycle or operation.

The machine will, therefore, continuously 125 operate to convey successive screws from the magazine by the escapement mechanism to the receiving foot which carries them to the work, the screw driver operating at the prop-

er time to drive the screw into the work, these operations being repeated continuously.

We claim:

1. A screw driving machine including a magazine for containing screws, an escapement mechanism immediately adjacent to the magazine for feeding screws from the magazine, a foot arranged to come to a position immediately adjacent to the escapement mechanism for receiving the screws from the escapement mechanism and conveying them directly to the work, a screw driver for driving the screws into the work, and means for lowering the foot and screw driver to the work immediately after the delivery of a screw to the foot.
2. A screw driving machine including a magazine for containing screws, an escapement mechanism immediately adjacent to the magazine for feeding screws from the magazine, a foot arranged to come to a position immediately adjacent to the escapement mechanism for receiving the screws from the escapement mechanism and conveying them directly to the work, a screw driver for driving the screws into the work, means for lowering the foot and screw driver to the work immediately after the delivery of a screw to the foot, and means for withdrawing the foot after the screw driver has started to drive the screw into the work.
3. A screw driving machine including a magazine for containing screws, an escapement mechanism immediately adjacent to the magazine for feeding screws from the magazine, a foot arranged to come to a position immediately adjacent to the escapement mechanism for receiving the screws from the escapement mechanism and conveying them directly to the work, a screw driver for driving the screws into the work, means for lowering the foot and screw driver to the work immediately after the delivery of a screw to the foot, means for withdrawing the foot after the screw driver has started to drive the screw into the work, and means for returning the foot to a position adjacent to the escapement mechanism and for raising the screw driver after the screw is driven into the work.
4. A screw driving machine including a magazine for containing screws, an escapement mechanism comprising a segment immediately adjacent to the magazine arranged to normally prevent delivery of screws from the magazine and having a notch adapted to receive one screw at a time, means for moving the segment to receive a screw directly from the magazine, and screw holding and driving means arranged to receive each screw directly from the segment.

5. A screw driving machine including a magazine for containing screws, an escapement mechanism comprising a segment immediately adjacent to the magazine arranged to normally prevent delivery of screws from the

magazine and having a notch adapted to receive one screw at a time, means for moving the segment to receive a screw directly from the magazine, screw holding and driving means arranged to receive each screw directly from the segment, and means for ejecting each screw from the segment and delivering it directly to the screw holding and driving means.

6. A screw driving machine including a magazine for containing screws, an escapement mechanism comprising a segment immediately adjacent to the magazine arranged to normally prevent delivery of screws from the magazine and having a notch adapted to receive one screw at a time, means for moving the segment to receive a screw directly from the magazine, screw holding and driving means arranged to receive each screw directly from the segment, and a feed slide associated with the segment for ejecting each screw from the segment and delivering it directly to the screw holding and driving means.

7. A screw driving machine including a magazine for containing screws, an escapement mechanism immediately adjacent to the magazine for feeding screws from the magazine, a foot arranged to come to a position immediately adjacent to the escapement mechanism for receiving the screws from the escapement mechanism and conveying them directly to the work, a screw driver for driving the screws into the work, and a single cam means for automatically lowering the foot and screw driver to the work immediately after the delivery of a screw to the foot.

8. A screw driving machine including a magazine for containing screws, a foot arranged to come to a position adjacent to the magazine for receiving the screws from the magazine and conveying them directly to the work, a screw driver for driving the screws into the work, means for lowering the screw driver to the work and a push rod operated by said means for simultaneously lowering the foot to the work.

9. A screw driving machine including a magazine for containing screws, a foot arranged to come to a position adjacent to the magazine for receiving the screws from the magazine and conveying them directly to the work, a screw driver for driving the screws into the work, cam means for lowering the screw driver to the work and a push rod operated by said means for simultaneously lowering the foot to the work.

10. A screw driving machine including a magazine for containing screws, escapement mechanism immediately adjacent to the magazine for feeding screws from the magazine, means arranged to come to a position immediately adjacent to the escapement mechanism for receiving the screws from the escapement mechanism and conveying them directly to the work, means for driving the screws into

the work, means for automatically lowering the receiving means and driving means to the work immediately after the delivery of a screw to the receiving means, and means for continuously operating the mechanisms in sequence to continuously drive successive screws.

11. A screw driving machine including a magazine for containing screws, escapement mechanism immediately adjacent to the magazine for feeding screws from the magazine, means arranged to come to a position immediately adjacent to the escapement mechanism for receiving the screws from the escapement mechanism and conveying them directly to the work, means for driving the screws into the work, and means for automatically lowering the receiving means and driving means to the work immediately after the delivery of a screw to the receiving means.

12. A screw driving machine including a magazine for containing screws, an escapement mechanism immediately adjacent to the magazine for feeding screws from the magazine, a foot for receiving the screws directly from the escapement mechanism and conveying them directly to the work, a screw driver for driving the screws into the work, a cam shaft, a cam on the shaft for operating the escapement mechanism, a lever, a cam on the shaft for operating the lever, the screw driver being operatively connected to the lever, and a push rod operatively connected to the lever for lowering the foot.

13. A screw driving machine including a magazine for containing screws, an escapement mechanism immediately adjacent to the magazine for feeding screws from the magazine, a foot for receiving the screws directly from the escapement mechanism and conveying them directly to the work, a combined horizontal and vertical slide mechanism carrying the foot, a screw driver for driving the screws into the work, a cam shaft, a cam on the shaft for operating the escapement mechanism, a lever, a cam on the shaft for operating the lever, the screw driver being operatively connected to the lever, and a push rod operatively connected to the lever for lowering the slide mechanism.

14. A screw driving machine including a magazine for containing screws, an escapement mechanism immediately adjacent to the magazine and including a pivoted segment and a feed slide for feeding screws from the magazine, a foot for receiving the screws directly from the escapement mechanism and conveying them directly to the work, a screw driver for driving the screws into the work, a cam shaft, a cam on the shaft for operating the segment, a cam on the shaft for operating the feed slide, a lever, a cam on the shaft for operating the lever, the screw driver being operatively connected to the lever, and a

push rod operatively connected to the lever for operating the foot.

15. A screw driving machine including a magazine for containing screws, an escapement mechanism immediately adjacent to the magazine and including a pivoted segment and a feed slide for feeding screws from the magazine, a foot for receiving the screws directly from the escapement mechanism and conveying them directly to the work, a combined horizontal and vertical slide mechanism carrying the foot, a screw driver for driving the screws into the work, a cam shaft, a cam on the shaft for operating the segment, a cam on the shaft for operating the feed slide, a lever, a cam on the shaft for operating the lever, the screw driver being operatively connected to the lever and a push rod operatively connected to the lever for operating the slide mechanism.

16. A screw driving machine including a magazine for containing screws, an escapement mechanism immediately adjacent to the magazine for feeding screws from the magazine, a foot for receiving the screws directly from the escapement mechanism and conveying them directly to the work, a screw driver for driving the screws into the work, a cam shaft, a cam on the shaft for operating the escapement mechanism, a lever, a cam on the shaft for operating the lever, the screw driver being operatively connected to the lever, an indexing device below the screw driver, a cam on the shaft for operating the indexing device, and a push rod operatively connected to the lever for lowering the foot.

In testimony that we claim the above, we have hereunto subscribed our names.

GRA C. BROWN.
GREGORY F. McNULTY.
